(57) **CLAIM**

We claim the ornamental design for a combined cosmetic holder and mirror, as shown and described.

DESCRIPTION

FIG. 1 is a perspective view of a combined cosmetic holder and mirror showing my new design with the top hinged cover in a partially opened position and the mirror component partially extending from the front storage slot; FIG. 2 is a front elevational view thereof with the top hinged cover in a closed position;

FIG. 3 is a rear elevational view thereof;

FIG. 4 is a left side elevational view thereof with the top hinged cover in an opened position and the mirror component fully removed;

FIG. 5 is a right side elevational view thereof;

FIG. 6 is a top plan view thereof with the top hinged cover in a fully opened position and the mirror component fully removed;

FIG. 7 is a bottom plan view thereof; and,

FIG. 8 is an additional perspective view thereof with the mirror component shown along the underside of the top hinged cover.

The broken lines within the several figures illustrate environmental structure only and form no part of the claimed design.
